UNITED STATES PATENT OFFICE.

JAMES D. HUMPHREY, OF TOWANDA, PENNSYLVANIA.

NUMBERING-MACHINE.

SPECIFICATION forming part of Letters Patent No. 399,991, dated March 19, 1889.

Application filed April 4, 1887. Serial No. 233,667. (No model.)

To all whom it may concern:

Be it known that I, JAMES D. HUMPHREY, a citizen of the United States, residing at Towanda, in the county of Bradford and State of Pennsylvania, have invented certain new and useful Improvements in Numbering-Machines; and I do hereby declare the following to be a full, clear, and exact description of the invention, such as will enable others skilled in the art to which it appertains to make and use the same.

My invention consists of a machine designed especially to stamp boots and shoes, &c., with numbers and letters to indicate their size, width, and the case in which they are contained. Although partially adapted to this purpose, the machine can be used whenever it is desired to stamp or print upon any suitable object numbers, letters, or other signs, and for which hand-stamps are now generally employed.

My invention is illustrated in the accompanying drawings, in which—

Figure 1 is a side elevation; Fig. 2, a similar view of the opposite side; Fig. 3, a front elevation; Fig. 4, a plan view; Fig. 5, a cross-section on line $y-y$ of Fig. 4; Fig. 6, a longitudinal section on line $x-x$ of Fig. 4; Figs. 7, 8, 9, 10, 11, 12, 13, and 14, details.

Referring to the drawings, there is shown mounted on a frame composed of two end pieces, A A', and two side bars, B B', a shaft C, having its bearings in boxes d on the opposite end pieces, A A'. Power is communicated to this shaft through cogs A² A³ from pulley A⁴ in end of lever-shaft B³, which shaft runs beneath the machine, and is mounted in hangers e e on the end pieces, A A'.

B⁴ is a drive-wheel on the shaft C. At the front end of the machine and secured to the end of the side bars, B B', is a frame, D, within which are mounted a number of marking or registering wheels.

D' are a series of wheels, each carrying in their faces ten numbers, from 1 to 0. These numbers are types secured in the wheels by binding pressure, the same being somewhat wedge-shaped and driven into the spaces provided for them. Each wheel is provided on one side with a toothed disk, e', and all are mounted on a headed shaft, E, journaled in a boss, E². The outer end of the shaft E is

screw-threaded and provided with a thumb-nut, E³. By tightening the thumb-nut the type-wheels are brought closely together upon the shaft E and held tightly thereon, so as not to be moved independently without first loosening the thumb-nut E³.

E⁴ are spindles secured in collars e⁴, and each of which carries at its inner ends a toothed disk, e⁵. These disks engage, respectively, with toothed disks e' on the type-wheels. The outer ends of said spindles are provided with thumb-nuts e⁶, whereby the numbers in the type-wheels may be changed during the stamping operation.

Secured on each of the spindles E⁴ is a ratchet, F, on the outside of the frame D, which engages with pawls f', secured to said frame. The teeth of the ratchets correspond in number to the type-numbers fixed in the wheels D', so that on turning a wheel by a spindle, E⁴, the distance of one notch a new number is presented on the upper surface of the type-wheel.

For convenience in setting the numbers, each tooth of a ratchet may be numbered to correspond to the numbers on the type-wheel with which it is connected, as shown. I have illustrated four type-wheels in position; but their number may be increased. In marking the uppers of boots and shoes these wheels are used to indicate the number of the case in which the articles are packed.

F² F³ are larger type-wheels adjoining the former ones and mounted at right angles thereto.

In marking boots and shoes and similar articles the type-wheel F² is used to indicate the width or other variations in the size of the shoe, and the type-wheel F³ is used to stamp the size of the shoe itself. The type-wheel F², provided with a hub, f³, is mounted and turns loosely on the shaft C, and the type-wheel F³, provided with a hub, f⁴, is also mounted loosely on the shaft C.

The front type-wheel, F², is for marking the variations in size, and is rotated by the following means: On the end of its hub f³ is secured a cog, g, and between this and the shaft journal-box a washer. This cog meshes with a cog, h, on a spindle, h', which has its bearings in end piece, A'. The outer end of the spindle h' is provided with a thumb-piece, j,

by which the spindle can be turned to rotate the wheel F^2 through cogs g and h . The wheel F^2 is provided with twelve spaces for types and one blank space.

5 To fix the wheel F^2 at any particular number, the spindle h' is provided with a spring holding device, I. This consists of a thumb-piece, j , and a plate, j' , in one piece and sliding on the spindle h' . The inner end of the 10 plate j' , facing the machine, is provided with thirteen small recesses j^2 , corresponding with the number of the type-spaces in wheel F^2 .

K is a pin projecting from the end piece, A' , of the machine toward the plate j' .

15 L is a spring coiled upon the spindle h' between an outer thumb-piece, j , and the inner plate, j' , the function of which is to press the holder I against the end piece, so that when the pin K enters one of the recesses j^2 20 the wheel F^2 will be held stationary until it is desired to present a new number to be stamped. When a new number is wanted, it is simply necessary to pull back the thumb-piece j and the plate j' against the pressure 25 of the spring and turn with thumb-nut j and the spindle h' . To facilitate the operation, the plate j' is provided with a pointer, j^3 , around which are printed numbers and a cipher to correspond with the numbers and 30 blank space in the wheel F^2 , so that by releasing the holder and turning the spindle h' until the pointer points to the desired number the wheel F^2 will be turned to present and be fixed at the same number. If no number 35 is desired to be printed, the wheel can be turned to the blank space and held there by the holding device I.

The mechanism for operating and controlling the wheel F^3 for marking the size of the 40 boot or shoe will now be described.

M is a plate secured on one side of the machine, having thirteen numbers, from 1 to 13, printed therein to correspond with the type-numbers of sizes in the wheel F^3 .

45 M' are thirteen keys arranged directly below said numbers, and each of which passes through a separate slot, m^3 , cut in plate M beneath each number and independently pivoted to a horizontal rod, m^2 , connected by 50 hangers to the side bar, B . Each key bears upon a collar, M^4 , fixed by a set-screw to a vertical rod, N . There are thirteen of these vertical rods extending up through the side bar, B , and through a plate, N' , and each is 55 provided with a collar, m^5 , fixed by a set-screw and a coiled spring on the rod between collar m^5 and the plate N' . Attached to each of the collars m^5 is a pin, m^6 , and these pins extend through slots m^7 in a plate, O . The 60 lower collars on the rods N , which form the bearings for the keys, can be raised or lowered to regulate the throw of the key, and the upper collars can be raised or lowered to regulate the tension of the springs and the consequent force by which the keys are operated.

65 P are separate lever-arms (thirteen in number) secured at one end by nuts and washers

to the tops of the rods N , and pivoted at the other end to a horizontal rod, P' . They are each provided near the center with a lug or tooth, p^2 , which are adapted to engage with pins r , arranged spirally on a sleeve, R , on shaft C . The pins r are also thirteen in number, to correspond with the number of arms, rods, and keys above described. The sleeve 70 R is secured at one end to the hub t of a sliding and rotary collar, S , on shaft C by means of set-screw t' , set in a slot, t^2 . At its opposite end the sleeve R is secured to the hub f^4 75 of type-wheel F^3 , and on said hub, between the end of the sleeve R and wheel F^3 , is placed a ratchet, f^5 , provided with thirteen notches and governed by a pawl, f^6 . The drive-wheel B^4 is provided with a hub, b^5 , having a conical head, against which the collar S is pressed, 80 the collar S having the edges of its bore beveled where it comes in contact with the conical hub. The collar S in its normal condition is pressed against the conical hub by means of a spring, T , placed around shaft C within 85 the sleeve R .

V is a rocking shaft carrying at its center a yoke, V' , whose arms v^2 v^3 bear against the sliding collar S . The shaft V is journaled in boxes v^4 on the side bars, and to one end of 90 the shaft is secured an arm, v^5 , to which is attached the plate O' . The plate O' is provided with fourteen teeth, w , having their upper surfaces rounded and their sides inclined, forming the thirteen inclined slots w^2 between 95 them. The pins m^6 on rods N extend through the slots w^2 and bear against one end of the upper part of the teeth when forced down.

W is a rod extending beneath the plate M , secured at one end to a hanger on said plate 100 and at the other end passing through the end piece, A' , and provided at that end with a thumb-piece, y , and a spiral spring, Z .

Y' are levers pivoted at their center on plate M , with their lower ends secured to rod 110 W and their upper ends inclined and shouldered, so as to engage with keys M' , which engagement is effected by the force of the spring Z when a key is pressed down, as hereinafter described.

115 Having thus described the mechanism for operating the type-wheel F^3 for printing the sizes, its operation is as follows: When it is desired to fix said wheel so that a certain size of boot or shoe may be stamped, one 120 of the keys M' opposite the desired size is pressed down, forcing the notched head of the lever Y' aside until the key passes it, when the shouldered head springs back and holds the key. In order that the levers Y' may be 125 easily pressed aside, their heads, against which the keys rest, are inclined, as shown. When a key is thus pressed down, a pin m^6 is pushed against the side of a tooth w of the plate O' , which action gives to plate O' an endwise 130 motion at the same time to the rocking shaft V , and pressing the arms v^2 v^3 of the yoke V' against the collar S with sufficient force to release it from contact with hub b^5 . This de-

pression of the key also lowers a lever, P, so that its lug or tooth p^3 will engage with a pin, r, on sleeve R when the sleeve R is rotated a sufficient distance. The release of the sleeve 5 R does not prevent it from further rotation on shaft C, but relieves the strain to which the sleeve would otherwise be subjected when the sleeve R comes in contact with the lug on lever P if the same connection of the sleeve 10 R and shaft C continued. When the engagement mentioned takes place, the sleeve R is then held stationary. As the pins r are each arranged on a line with a number on plate M, and at the same time in a line with a corresponding 15 number in the size-wheel F^3 , and as the wheel F^3 is secured to the sleeve R, it follows that when the rotation of the sleeve R is stopped the number in wheel F^3 corresponding with the number of the size on plate M on a line with the key struck will also be stopped 20 and held for printing. The ratchet and pawl connected with the hub of wheel F^3 acts to hold the wheel against backward rotation. When another key is depressed, it acts to 25 simultaneously release the former key, as, striking the head of a lever Y', it forces forward the spring-rod W, which carries the notched head of the other lever Y' off the other key, which, under the action of the spring on rod 30 N, is brought up to its original position. When any key is depressed and it is desired not to work the size-wheel, the rod W is pressed upon from the end, which releases the key last worked, and when all the keys are 35 up the wheel F^3 will continue to revolve with the sleeve R and shaft C until another key is depressed.

F^{10} is a pressure-plate over the type-wheels, suspended from rods J', connected to an arm, 40 J², pivoted in a fulcrum, J³, and which rod is connected to a vertical rod, J⁴, by means of a collar and set-screw, J⁵. The rod J⁴ is secured to an eccentric-strap, J⁶, by means of a plate, j¹⁰, screwed to the strap, and J⁷ is the 45 eccentric, attached to the axle of which is a pinion, J⁸, connecting a worm, J⁹, on the lower shaft, B³. The pressure-plate has an india-rubber or other elastic pad, J¹⁰.

On rod J', between a nut on the head of the 50 rod, is fixed a spring, J¹¹, to give to the pressure-plate a yielding motion.

L⁶ is an inking-ribbon extending over the type-wheels and wound on spools L⁸.

The upper of the shoe or boot or other article to be stamped is placed over the type-wheels beneath the pressure-plate, and it will be seen by the description of the parts and their operation above given that the article 55 can be marked with a series of numbers, or with any one number without the others, or with any set or sets or combination of numbers. It will be seen, also, that by the separable and independent arrangement of the parts any one part can be easily removed for 60 the purpose of repairing or for being replaced by another.

Having thus described my invention, what I

claim, and desire to secure by Letters Patent, is—

1. In a printing and stamping machine, the 70 combination with the driving-shaft, of a drive-wheel, a sliding collar, and a type-wheel, all on said shaft, and a sleeve over said shaft, connected at its opposite ends to said collar and type-wheel, the said sliding collar adapted 75 to engage with a hub of the drive-wheel, whereby when the shaft is rotated the said remaining parts will also rotate, substantially as described.

2. In a printing and stamping machine, in 80 combination with a rotating shaft, a sleeve on said shaft, a type-wheel carried by said shaft and provided with a hub to which said sleeve is secured, the sliding collar and its hub on the opposite end of the shaft, to which the 85 sleeve is also secured, the drive-wheel provided with a hub having a conical head, and the spring within said sleeve and around said shaft, whereby the said collar is pressed against the drive-wheel and the said cylinder and 90 type-wheel given a rotary movement, substantially as described.

3. In combination with the keys, the vertical spring-rods provided with pins, the plate provided with slots through which said pins 95 extend, the toothed bar, the rocking shaft to which said toothed bar is connected, the yoke and its arms carried by said shaft, and the sliding collar, to which is attached the sleeve carrying the pins, whereby the tension of the 100 said sleeve on the driving-wheel is released, substantially as described.

4. In combination with the keys, the vertical rods provided with upper and lower adjustable collars, against which lower collars 105 the said keys bear, the springs on the rods in connection with and between a plate and the upper adjustable collars, and the shouldered levers across the top, whereby the tension of 110 said springs and the force of the keys on said rods and levers can be regulated, substantially as described.

5. In combination with the rotating sleeve provided with the pins arranged spirally, the vertical rods and holding-arms, the plate M, 115 having characters and provided with slots m³, the keys M', the levers Y', pivoted to plate M and provided with the shouldered and inclined heads, and the horizontal spring-rods W, to which said levers are connected, 120 whereby a key when operated to fix the said sleeve is held at a certain character until released by the pressure of a successive key, or by pressure on the end of the horizontal spring-rod, substantially as described. 125

6. In combination with the wheel F^2 , provided with a number of type and one blank space, a hub, f^3 , and a cog, g, and the spindle for turning the same, provided with a cog, h, meshing with cog g, the spring holding device I, consisting of thumb-piece j, spring L, and the plate j' on said spindle, the pointer j³, and characters printed on the end of the machine around said pointer, corresponding 130

with those on the type-wheel F^2 , the said plate j' provided with recesses j^2 , corresponding in number with the number of type-spaces in the wheel F^2 , and the pin K , projecting from the end of the frame A' , whereby the said type-wheel is turned and fixed at the desired character, substantially as described.

7. The independent type-wheels, each provided with a toothed disk, in combination with a shaft on which said wheels and disks are closely mounted, and separate spindles, each provided with a toothed disk to engage with a disk on a type-wheel, whereby each of the type-wheels is separately and independently adjusted, substantially as and for the purpose described.

8. In combination with the adjustable type-

wheels, the separate spindles and the toothed disks on the wheels and spindles for adjusting each of said wheels independently of each other, a ratchet on each of said spindles, and a pawl for each ratchet secured to the frame, the teeth of said ratchets corresponding in number to the types in said wheels, whereby on turning a spindle one notch a new number is presented on the type-wheel, substantially as described.

In testimony whereof I affix my signature in presence of two witnesses.

JAMES D. HUMPHREY.
